To all whom it may concern:

Be it known that I, WILLIAM T. HOLLEY, a citizen of the United States, residing at Morristown, in the county of Hamblen and

In the drawing the figure is a perspective view of a kitchen-cabinet embodying the herein-described design.

The base portion 2 of the body is provided at its front side with a plain rectangular panel 3, with rectangular end panels 4 and pendent corner-leg projections 5. The rectangular box-base 2 is surmounted by a cabinet-top 6, provided with a horizontal rectangular flat top board 7, a narrow vertical ledge projection 8, extended above the plane of the top board at the rear edge thereof, and a front inclined door-panel 10. The front inclined door-panel 10 is of a width nearly equaling the height of the said cabinet-top and is provided at its end edges with straight strips 11.
